(57) **CLAIM**

The ornamental design for a display screen portion with graphical user interface, as shown and described.

DESCRIPTION

FIG. 1 is a first image in a sequence for a front view of a display screen portion with graphical user interface, according to an embodiment;

FIG. 2 is a second image in the sequence for the front view of the display screen portion with graphical user interface, according to an embodiment;

FIG. 3 is a third image in the sequence for the front view of the display screen portion with graphical user interface, according to an embodiment; and

FIG. 4 is a fourth image in the sequence for the front view of the display screen portion with graphical user interface, according to an embodiment.

The outermost broken line perimeter shows a display screen portion with graphical user interface and is included for the purpose of illustrating a portion of the article and forms no part of the claimed design. The remaining broken lines illustrate portions of the graphical user interface and form no part of the claimed design. The appearance of the front view of the display screen portion with graphical user interface transitions between the images, as shown and described in FIGS. 1-4 in the embodiment. The process or period in which one image transitions to another image forms no part of the claimed design, and any intervening images between the images shown also form no part of the claimed design.
